[57] ABSTRACT

An incinerating waste disposal plant, such as a dry sanitary toilet, including a fuel burner and an oscillator ignition system for igniting the fuel. In the system disclosed, the oscillator is one in which the core of the inductive component is driven to saturation and provides intermittent high voltage across an igniter spark gap.

SHEET 2 OF 2

FIG. 2

FIG. 3

INCINERATOR AND IGNITION SYSTEM COMBINATION

BACKGROUND OF THE INVENTION

1. Field of the Invention

This invention relates to improvements in incinerating waste disposal plants and especially improvements in dry sanitary incinerating toilets. The invention also relates to incinerating toilets especially adapted for installation in the field or in moving vehicles, relying on a D.C. source of electricity.

2. Brief Description of the Prior Art

Incinerating toilets are becoming more and more important as pollution problems grow. For example, such toilets have found use in residences where suitable waste disposal is not available, camping areas, military camps, in installations on vehicles such as house trailers and diesel trains, cottages, boat houses and many other areas. Usually such toilets operate utilizing a burning cycle followed by a cooling cycle for cooling the combustion chamber after the waste is destroyed. It is important to have positive and sure ignition of the burner in order to prevent fire hazards or even explosions.

Previous incinerating toilets designed for use in conjunction with a D.C. source of electricity, e. g., in railroad locomotives, have employed expensive inverters to change the D. C. current to 60 cycle A.C. so that the current can be used by standard A.C. components in the incinerating toilet. One of the important roadblocks against using D.C. directly has been the lack of a dependable ignition system which can use the 74 volt D.C. standard power on a locomotive.

SUMMARY OF THE INVENTION

The present invention provides a new and useful incinerating waste disposal plant in the form of a dry sanitary toilet having a new and improved D.C. ignition system. The ignition system uses an oscillator to apply a high voltage across a spark gap. The high voltage is produced as a rapid plurality of intermittent discharges across the spark gap such as to have the appearance of a continuous spark. The oscillator in the preferred form is one in which the core of the inductive component is driven to saturation.

While an illustrative embodiment of the invention is shown in the drawings and will be described in detail herein, the invention is susceptible of embodiment in many different forms and it should be understood that the present disclosure is to be considered as an exemplification of the principles of the invention and is not intended to limit the invention to the embodiment illustrated.

BRIEF DESCRIPTION OF THE DRAWINGS

FIG. 1 is a vertical section through one form of the incinerating toilet of this invention;

FIG. 2 is a wiring diagram of an oscillator which can be used in the ignition system of the toilet of FIG. 1; and

FIG. 3 is a diagrammatic showing of a wheeled vehicle, usually a diesel locomotive, with the toilet of FIG. 1 installed thereon.

DESCRIPTION OF THE PREFERRED EMBODIMENTS

To a large extent the present invention provides improvements and modifications in an incinerating toilet

such as that shown in Frankel et al U. S. application Ser. No. 108,050 and, as background material and so far as description of the structure and operation of an incinerating toilet is concerned, U. S. application Ser. No. 108,050 is hereby incorporated herein by reference.

Referring to FIGS. 1 and 3, the incinerating toilet includes a tear drop shaped cabinet 20 with a housing 22 and an outer side wall skirt 24 secured by suitable spacer members to the housing 22 to define an air space 26 between housing 22 and skirt 24. Air can enter air space 26 at the bottom of skirt 24. Also, ports 28 are provided around the upper portion of housing 22 for entry of air into air space 29 within housing 22 from space 26. Ports 28a (FIGS. 1 and 3) are also provided for more direct entry of air into the lower portion of space 29.

Housing 22 also has a central waste receiving top opening 30 with a seat 32, with seat opening 32a generally registering with the opening 30. A cover 34 is secured to a hinge rod 36 for pivotal movement with rod 36 between a down or closed position and an up or open position. Spacers 34a are provided on the bottom surface of cover 34 for spacing cover 34 from seat 32 when cover 34 is in its closed position. Seat 32 is secured to brackets 37 which pivot on hinge rod 36 for raising and lowering seat 32. Seat 32 also has spacers 32b for spacing it from the top wall of the housing 22 when in down position.

Mounted in the bottom of cabinet 20 is a large and deep combustion pot defining the receiving and combustion chamber 38. The receiving and combustion chamber 38 is insulated on its outer surface by layers of high temperature (up to 2,000°F. or higher) insulation indicated collectively at 40. An oil burner 42 is mounted at an elevated position at about the lip of the receiving and combustion chamber 38 and trained downward at an angle to the side wall of the receiving and combustion chamber, generally toward the center of the combustion chamber for directing a flame into the combustion chamber. The oil burner illustrated is a Gulf-type aspirator burner (See Biber et al. U.S. Pat. No. 3,119,604) having the normal float chamber 46 with about a three inch negative pressure lift front float chamber 46 to the burner 42. Oil is supplied to burner 42 from float chamber 46 through an oil line 48 which includes and is controlled by a fuel solenoid or oil-flow control valve 54. A motor driven compressor can be used to supply air to burner 42 via air line 50 as described in the above mentioned Frankel et al application Ser. No. 108,050. The oil is aspirated by the air in the burner and upon ignition the burner supports a flame at its lower end. Oil from a suitable source of supply is delivered to the float chamber 46 via an oil inlet line 52.

Alternatively a gas burner can be used, supplied with propane or like fuel from a tank or cylinder, e. g., aboard a locomotive.

As seen in FIG. 1 the oil burner igniter 44 includes a pair of closely spaced electrodes 56 and 58 supplied with a high voltage from an oscillator 60 so that a spark is created between the electrodes spaced laterally from the outlet of burner 42. An orifice or port 62 is machined or cast into the wall of the burner air chamber at a 45° angle to the axis of the burner to direct a stream of air from the burner air chamber through electrodes 56 and 58 and into the flame cone area at the

burner flame holding port. As the air passes through the spark gap of igniter 44 it is apparently ionized by the spark and the ionized air carries or blows the ignition spark into the cone of combustible spray ensuing from the end of burner 42. The spark thereby ignites the burner and after ignition the orifice 62 continues to supply a small amount of combustion air directly to the flame, in addition to the combustion air used to atomize the fuel within burner 42.

In FIG. 2, the oscillator 60 is illustrated in detail. Oscillator 60 includes a first controllable conduction device 100, as an NPN transistor, a second controllable conduction device 102, as a second NPN transistor, and a core 106 of magnetizable material which determines the frequency of oscillation of the circuit. Essentially, the oscillator circuit operates as a free-running magnetic multivibrator in which the frequency of oscillation is determined by the speed of magnetization of the material in core 106 and the strength of the magnetizing forces on the core.

Core 106 is formed of magnetizable material such as permalloy 80 (DU-37-6D), having a square cross-section, as three-eights X three-eights inches (9/64 square inches). The core 106 forms a part of a step-up transformer having three primary windings and one secondary winding. One primary winding 110 consists of 25 turns of number 36 wire wrapped about core 106. A pair of primary windings 112 and 114 each consist of 76 turns of number 36 wire wound bifilar about the core. A single voltage step-up secondary winding 116 consists of 5,000 turns of number 42 wire wound about the core 106. The opposite ends of secondary winding 116 are directly coupled to leads 55 and thence to the electrodes 56 and 58 which form a spark gap, having a distance therebetween of three-sixteen inch.

The transistors 100 and 102 are oppositely driven by primary windings 112 and 114, respectively. To power the oscillator 24, a source of DC potential is connected between a positive source terminal 120 and a negative source terminal 122, such as 78 volts DC. A 10 microfarad capacitor 124 shunts the terminals 120 and 122. Positive terminal 120 is coupled to a junction 126 to which one side of each of the primary windings 112 and 114 is connected. The opposite side of winding 112 is coupled to the collector electrode of transistor 100, the emitter electrode of which is directly connected to negative terminal 122. Similarly, the opposite side of winding 114 is coupled to the collector electrode of transistor 102, and the emitter electrode is coupled to negative terminal 122.

Primary winding 110 has one side directly coupled to the control or base electrode of transistor 100, and the other side coupled through a 0.02 microfarad capacitor 130 and a parallel connected 470 ohm resistor 132 and a 0.01 microfarad capacitor 134 to the control or base electrode of transistor 102. The base-emitter junctions of both transistors 100 and 102 are shunted by a pair of diodes 140 and 142, respectively. The base electrode of transistor 100 is also coupled through a 100 kilohm resistor 144 to positive terminal 120.

In operation, when potential is first applied across terminals 120 and 122, some current passes through resistor 144 to the base of transistor 100, forward biasing the transistor into its conducting state. This allows a current flow from terminal 120, junction 126, and through primary winding 112 and the conducting transistor 100 to negative terminal 122. The primary wind-

ings 110, 112 and 114 are mutually coupled as indicated by the dots in FIG. 2. The current through primary winding 112 induces a current in winding 110 which drives transistor 100 harder into conduction, resulting in a stronger current in winding 112, which in turn forward biases or drives transistor 100 still harder. The resulting regenerative action quickly saturates transistor 100. Depending on the speed of magnetization of the material in the core 106, the core later becomes saturated.

When the core 106 saturates, the drive from winding 110 begins to decay. During the time transistor 100 was forward biased, capacitor 130 had been charging with a positive polarity at the junction between capacitor 130 and capacitor 134. When the output of winding 110 starts to decay, capacitor 130 is effective to drive transistor 102 into its forward biased state. The resulting current through winding 114 reverses the drive from winding 110, causing transistor 102 to be driven harder into conduction. The resulting regenerative action is similar to the action previously described for transistor 100. Capacitor 130 now recharges in the opposite direction so as to start transistor 100 conducting again when the core 106 again saturates. Resistor 132 is used to limit current drive to transistor 102, and capacitor 134 causes an increase in the switching speed.

Oscillator 60 thus drives the core of the transformer into saturation at short time period after the pair of transistors 100 and 102 are alternately switched from saturation to cut-off. The frequency of oscillation is thus determined by the material in the core, and for the given illustrative values of components, is approximately 11 kilohertz. Due to the step-up action of the transformer, the secondary winding 116 produces across the gap formed by electrodes 56 and 58 a peak output voltage of approximately 5,000 volts. The rapidity of intermittent peak out-put voltages (11,000 per second in the system described) across the gap creates a seemingly continuous spark, assuring combustion of the fuel-air mixture at burner 42. The spark is capable of lighting even solid fuels such as paper, wood and coal.

Although the device as illustrated in FIG. 1 includes motor driven exhaust blower 64 for exhausting the combustion chamber through vent 66, one form of the device for railroad use omits the blower 64 and relies entirely on a venturi system for venting the combustion chamber 38 as described in Frankel et al application Ser. No. 108,050. Such a venturi system is shown in FIG. 3 in the form of an induction Tee which includes a connector duct 166 for connecting the device to the exhaust outlet 66 and an induction flue duct 168 for connection to a suitable venting stack or flue. The induction Tee is driven by a source of pressure air supplied by an air supply tube 170 which extends approximately to the center of the juncture of connector duct 166 and induction flue duct 168. A connector 172 is provided at the lower end of tube 170 for connecting tube 170 to a suitable high volume source of air so that air can be delivered upward through tube 170 to create a venturi effect for drawing combustion gases from outlet 66 and through the connector duct 166. The combustion gases are vented upward by the induction flue duct 168 to the exterior. Downward or side venting can also be used. The venturi venting effect can be used either in addition to or in the absence of the blower fan 56.

FIG. 3 diagrammatically illustrates the incinerating toilet mounted on a locomotive, caboose or elsewhere on a railroad train. A wheeled carriage such as a diesel locomotive is represented generally by the reference numeral 200. The locomotive 200 is equipped with a conventional diesel fuel tank 174, an air brake reservoir 176 and one or more traction motor blowers providing a source of air at low pressure and at high volume as represented by "traction motor air" box 178. A fuel line 180 extends from the fuel oil reservoir 174 to fuel oil line 52 and includes a D.C. fuel oil cut-off solenoid valve 181 and a pressure reducing valve 182 for reducing pressure of oil (or gas) supplied from tank 174, in this case diesel fuel. The fuel in a diesel fuel tank is boosted to 30 to 35 psig pressure before injection into the engine so a pressure reducing valve 182 is used to reduce the pressure to a much lower level, e.g., about 8 psig or less, for delivery to the float valve chamber 46 and subsequent delivery to the burner 42. A filter 185 is also provided in the fuel line 180.

An air line 186 extends from the air brake reservoir 176 through a pressure reducing valve 188 and a D.C. on-off control solenoid 190 and connects to air line 50 to supply combustion air to burner 42. The pressure reduction valve 188 reduces the pressure of air from the air brake reservoir from its normal pressure of about 140 psig to a much lower pressure, e.g., about 4 psig, for use by the burner 42.

Traction motor cooling blowers are used in a locomotive to blow air over and cool the traction motors. A small portion of this high volume low pressure air represented at 178 is delivered through a duct as shown at 192 which is connected at connector 172 for directing the air upwardly through tube 170 to drive the induction Tee or venturi system for exhausting the dry sanitary toilet. Where traction motor air is not available, a blower can be used. The outlet of flue duct 178 is vented by suitable duct work 192 to the exterior through the roof (or floor, depending on venting arrangement) of the locomotive. Because the sources of fuel combustion air and venturi actuating or exhausting air are readily available on the locomotive, the dry sanitary toilet unit provides for very convenient installation in minimal overall space. Further, the device does not depend on actual motion of the locomotive for operation.

At times and especially during the hot summer months when ambient temperatures in the short hood section of a locomotive are often as high as 120°F., it is desirable to cool the oscillator. For this purpose a small air bleed line 196 is connected to line 50 and the outlet end of bleed line 196 is positioned near oscillator 60 for the purpose of blasting a small amount of air onto the oscillator box. As the air leaves the bleed line 196 there is also a small amount of expansion of the air which results in a small amount of actual refrigeration. This provides for a cooler running oscillator without the expense of a large heat sink.

The unit includes the rear top cabinet 202 which contains all of the electrical components needed for the operation of the device, e.g., the oscillator circuit, fuel and air control solenoids 181 and 190 and/or 54, pressure reducing valves 182 and 188, and flame sensor system. Other electrical components, when used, can also be mounted in cabinet 202 for quick and convenient access as described in Frankel et al application Ser. No. 108,050. The device can also employ the variable vent

204, the heat sensitive cooling switch, the sail switch 206, the timer system, and the trap door 208 and linkages and other features described by Frankel et al. In using the incinerating toilets of the present invention, it has been found that a single device can readily accommodate the requirements of a crew of 12 men each working day with an average of five uses per man per day. The sterilizing flame destroys all bacteria and virtually eliminates any pollution problems. The device does not involve any water consumption or use of chemicals and does not produce raw sewage or cause any problems with regard to flushing and emptying, handling or pumping or the pollution dangers of operating a water toilet for as many as 60 times a day. The device is easily serviceable and inexpensive to operate, costing only pennies a day for fuel. It can be installed in towers, shops, work-sheds or any other place where conventional recirculating, holding, septic or sewage systems are too costly, impractical or impossible to use. Further, it finds use in climates where water toilets will freeze. More specifically, the device can be installed in vacation homes, traveling construction office trailers, industrial buildings, tug boats, house boats, warehouses, farms, mines, garages, marinas, fuel pumping and communicating relay stations, highway rest and toll stations and any other place where convenience and economy are desired.

In the form of the device especially adapted for use by the railway industry, the device can be installed in cabooses, bunk or business cars and it can be installed as easily as a household dryer or an oil fired space heater. A gas or fuel oil line, electrical connection and a flue are all that are required. The improved igniter gives sure-fire ignition in all installations.

I claim:

1. An incinerating system comprising a combustion chamber, combustible means for burning in the combustion chamber, means defining a spark gap in spark 40 delivering proximity to said combustible means, oscillator means for applying a voltage across the spark gap for igniting the combustible means, said oscillator comprising a core of magnetizable material capable of being driven into and out of saturation, winding means 45 inductively coupled with said core, controllable conduction means, and circuit means connecting said controllable conduction means to said winding means for driving said core alternately into and out of magnetic saturation at a frequency controlled by the speed of magnetization of the core and the magnetizing forces produced by said winding means.

2. The system of claim 1 wherein said winding means includes primary winding means coupled by said circuit means to said controllable conducting means and secondary winding means magnetically coupled to said primary winding means, the out-put of said oscillator being provided across said secondary winding means.

3. The system of claim 1 wherein said controllable conduction means includes a pair of variable conduction devices, said circuit means connecting said pair of devices and said winding means as a multivibrator with a time constant controlled by the magnetizable material in said core.

4. The system of claim 3 wherein said winding means includes a first primary winding associated with one of said pair of devices and a second primary winding associated with the other of said pair of devices, and series

means connecting each of said primary windings in series with its associated variable conduction device.

5. The system of claim 4 wherein said winding means further includes a third primary winding mutually coupled to said first and second primary windings, each of said variable conduction devices includes two output electrodes and at least one control electrode, said series means connecting the first and second primary windings in series with the output electrode of the associated devices, and control means coupling said third primary winding to the control electrodes of said pair of devices.

6. The system of claim 5 wherein said control electrodes of said one and other devices are coupled to opposite sides of said third primary winding to alternately drive said devices into opposite conduction states.

7. The system of claim 6 wherein said circuit means includes a source of potential, and resistive means connecting said potential source to one of said control electrodes.

8. The system of claim 6 wherein said control means includes capacitor means connected in series between one side of said third winding and the control electrode of one of said devices.

5 9. The oscillator of claim 8 wherein said control means includes second capacitor means in the series connection for increasing the frequency of oscillation.

10 10. An incinerating system comprising a combustion chamber, combustible means for burning in the combustion chamber, means defining a spark gap in spark delivering proximity to said combustible means, and oscillator means for applying a voltage across the spark gap for igniting the combustible means, and means for cooling said oscillator.

15 11. The system of claim 10 wherein said burning means is a fuel burner having an air supply and said cooling means comprises a bleed line from said air supply to blast air on said oscillator.
